tion of the manually operable traverse wheel 35. A table positioning and indexing mechanism may comprise a stop dog 45 which is adjustably supported by a pair of clamping bolts 46 and 47 in a T-slot 48 formed in the front edge of the work supporting table 11. A stop block 50 is fixedly mounted on the dog 45 and is provided with a plurality of stepped stop abutments 51, 52, 53 and 54 which are formed and face longitudinally to correspond with the shouldered portion to be ground on the work piece 17. The stop block 50 is fastened to the front face of the dog 45 by a pair of screws 55 to facilitate removal of the same when desired. A stop block 50 is provided for each different work piece to be ground and the stepped faces thereon are accurately formed and spaced to correspond with the spacings of shouldered portions on the work piece to be ground. It will be readily apparent from the foregoing disclosure that by changing the block 50, the mechanism may be readily set up for grinding any desired shouldered type work piece having a plurality of shouldered portions thereon to be ground.

A visible indicating mechanism is provided which is arranged to aid in successively positioning the table 11 in predetermined grinding position. This mechanism may comprise a bracket 60 which is fixedly supported on the front of the machine base. The bracket 60 is provided with two upwardly extending arms 61 and 62 which serve pivotally to support a rocking plate 63. The arms 61 and 62 are provided with a pair of aligned opposed pivot screws 64 and 65, respectively, the inner ends of which are cone shaped (Fig. 2) to mate with conically shaped apertures formed in opposite side faces of the rocking plate 63. The rocking plate 63 is provided with a cylindrically shaped box-like portion 66 which serves as a support for a dial indicator 67. A supporting stud 68 of the dial indicator passes through a hole in the rocking plate 63 and is held in fixed position therein by means of a set screw 69 (Fig. 4).

The pivotally mounted plate 63 supports a bell crank lever 70 (Fig. 3) having one arm 71 which is arranged to engage an actuating plunger 72 of the dial gauge 67. Another arm 73 of the bell crank lever 70 serves to engage the stepped stop abutment surfaces 51, 52, 53 and 54 of the stop or positioning dogs 45. The bell crank lever 70 is pivotally supported by means of a stud 74 which is fixedly supported on the pivotally mounted plate 63. A pair of stop screws 75 and 76 supported in bosses 77 and 78, respectively, formed integrally with the pivotally mounted plate 63 serve to limit the rocking movement of the bell crank lever 70 in either direction.

In order to accurately position the table 11 for grinding successive shouldered portions on the work piece 17, it is desirable to provide a suitable mechanism for successively positioning the arm 73 of the bell crank lever 70 in operative position relative to stop abutments 51, 52, 53 and 54 of the stop dog 45. This is preferably accomplished by a manually operated, cam actuated mechanism comprising a cam 80 which is fixedly supported on a rotatable shaft 81 which is journaled in bearings 82 and 83 formed in the bracket 60. The cam 80 is provided with a plurality of locating surfaces 84, 85, 86 and 87. A manually operable lever 88 is mounted on the left-hand end of the shaft 81 (Figs. 2 and 3) by means of which the cam 80 may be readily rotated to the desired and predetermined position to locate the

arm 73 of the bell crank 70 relative to the stop abutments 51, 52, 53 and 54 of the stop dog 45. The locating surfaces of the cam 80 are arranged to engage a surface 89 formed on the under side of the pivotally mounted plate 63. In the position of the parts (Fig. 4), the cam surface 84 is operative to position the arm 73 in an operative position relative to the stop abutment 51.

After the first shoulder on the work piece 17 has been ground to the desired and predetermined extent, the manually operable lever 88 is swung in a counterclockwise direction into the broken line position 88a (Fig. 4) to shift the cam 80 so that cam face 85 engages the face 89 on the plate 63. This movement swings the plate 63 to position the arm 73 in position 73a (Fig. 4) so that it is positioned in the path of movement of the stop abutment 52.

Similarly, after the second shoulder on the work piece 17 has been ground, the manually operable lever 88 may be again shifted in a counterclockwise direction into broken line position 88b to position the cam surface 86 in engagement with the surface 89 on the pivotally supported plate 63. This movement serves to rock the plate 63 so that the arm 73 of the bell crank lever 70 assumes position 73b (Fig. 4), in which position it lies in the path of the stop abutment 53. Similarly, when the lever 88 is again shifted in a counterclockwise direction into broken line position 88c to position the cam surface 87 in engagement with the surface 89, the plate 63 is again rocked in a counterclockwise direction to position the arm 73 in position 73c so that it lies in the path of the stop abutment 54.

The mechanism above described is shown set up for limiting and determining the table position as it is moved in a direction toward the right. If desired, the mechanism may be readily set up in a similar manner to indicate and determine table positions during its movement toward the left. The stud 74 together with the bell crank lever 70 supported thereby may be removed from the position shown in Fig. 3 and the stud 74 inserted in a threaded aperture 95. The stop abutment plate 50 may then be interchanged with a plate of the proper design. The stop screw 75 may be shifted into the threaded aperture 96 formed in a boss 97 projecting upwardly from the plate 63. The screw 75 in the new position together with the screw 76 will limit the rocking movement of the bell crank lever when set up to locate the table during a movement toward the left.

The operation of this improved table indexing and positioning mechanism will be readily apparent from the foregoing disclosure. Assuming the parts to have been previously adjusted and the stop abutment plate 50 of the proper design for the work piece 17 being ground to have been fixed in position on the dog 45 and the dog 45 adjusted to a predetermined position along the table 11, and assuming the lever 88 is in the full line position (Fig. 4), the manually operable hand wheel 35 is rotated to move the table 11 toward the right. As the table 11 approaches the desired and predetermined position, the stop abutment 51 engages the arm 73 of the bell crank lever 70 and rocks the bell crank lever 70 in a clockwise direction (Fig. 3). This movement serves to move the actuating plunger 72 of the dial indicator 67. The movement of the table 11 is continued until the dial indicator reads zero, namely, until the table is located precisely in the desired and predetermined position.

After the table has been thus located, the feeding mechanism may be actuated to cause an in-feeding movement of the grinding wheel 26 to grind the first shoulder on the work piece 17, after which the grinding wheel 26 is moved to a rearward or inoperative position. The control lever 88 is then moved in a clockwise direction into broken line position 88a to swing the plate 63 in a counterclockwise direction (Fig. 4) so as to position the arm 73 of the bell crank lever 70 in position 73a. The table 11 may then be moved a further distance toward the right until the stop abutment 52 (Fig. 3) engages the arm 73 of the bell crank lever 70 and rocks it to shift the dial indicator plunger 12 until the dial indicator reads zero, in which position the work piece is precisely positioned for grinding a second shouldered portion on the work piece.

After the second shoulder has been ground to the desired extent and the grinding wheel 26 has been removed to a rearward or inoperative position, the manually operable lever 88 is again moved in a counterclockwise direction into broken line position 88b to further swing the plate 63 so that the arm 73 of the bell crank lever assumes position 73b so that it lies in the path of the stop abutment 53, in which position the third shoulder on the work piece may be ground to the desired and predetermined extent. The manually operable lever 88 may then be swung further in a counterclockwise direction into position 88c, in which position the cam face 88 positions the rocking or pivotally mounted plate 63 in position so that the arm 73 of the bell crank lever 70 assumes position 73c and lies in the path of the stop abutment 54 for positioning the table in a fourth predetermined position for grinding a fourth shouldered portion on a work piece to the desired and predetermined extent.

As previously explained, the stop abutment plate 50 may be readily interchanged for a plate designed and made for positioning the table to grind any shouldered work piece to position the table 11 during its movement either toward the right or toward the left, depending upon the nature of the work piece to be ground.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a grinding machine having a base and a table slidably mounted thereon, a stop adjustably mounted on one of said parts having a plurality of spaced stop surfaces, an adjustable member on the other of said parts, a dial indicator on said member, a lever on said member arranged to actuate said indicator, said lever being arranged in the path of one of said stop surfaces, and means successively to position said member and lever in the path of successive stop surfaces on said stop dog.

2. In a grinding machine having a base and a table slidably mounted thereon, a stop adjustably mounted on one of said parts having a plurality of spaced stop surfaces, an adjustable member on the other of said parts, a dial indicator on said member, a lever on said member

arranged to actuate said indicator, said lever being arranged in the path of one of said stop surfaces, and manually operable means successively to position said member and lever in the path of successive stop surfaces on said stop dog.

3. In a grinding machine having a base and a table slidably mounted thereon, a stop adjustably mounted on one of said parts having a plurality of spaced stop surfaces, an adjustable member on the other of said parts, a dial indicator on said member, a lever on said member arranged to actuate said indicator, said lever being arranged in the path of one of said stop surfaces, and means including a cam successively to position said member and lever in the path of successive stop surfaces on said stop dog.

4. In a grinding machine having a base, a table slidably mounted thereon, an adjustable stop mounted on one of said parts having a plurality of spaced stepped stop surfaces, a pivotally mounted platen on the other of said parts, a dial indicator on said platen, a bell crank lever pivotally supported on said platen, one arm of said lever being arranged to actuate said dial indicator, the other arm of said lever being arranged in the path of movement of one of said stop surfaces, and means to tilt said platen intermittently and successively to position said latter arm in the path of successive stop surfaces on said stop dog.

5. In a grinding machine having a base and a reciprocable work supporting table mounted thereon, an adjustable stop on one of said parts having a plurality of stepped stop surfaces, a pivotally mounted platen on the other of said parts, a dial indicator on said platen, a bell crank lever pivotally supported on said platen, one arm of said lever being arranged to actuate said dial indicator, the other arm of said lever being arranged in the path of movement of one of said stop surfaces, and means including a cam to rock said platen successively to position said latter arm of the bell crank lever in the path of successive stop surfaces on said dog.

6. In a grinding machine having a base and a reciprocable work supporting table mounted thereon, an adjustable stop on one of said parts having a plurality of stepped stop surfaces, a pivotally mounted platen on the other of said parts, a dial indicator on said platen, a bell crank lever pivotally supported on said platen, one arm of said lever being arranged to actuate said dial indicator, the other arm of said lever being arranged in the path of movement of one of said stop surfaces, a rotatable cam to rock said platen, said cam being shaped to locate said platen in one of a plurality of positions, and a manually operable lever to actuate said cam.

7. In a grinding machine having a base and a reciprocable work supporting table mounted thereon, an adjustable stop on said table having a plurality of stepped stop surfaces, a pivotally mounted platen on said base, a dial indicator on said platen, a bell crank lever pivotally supported on said platen, one arm of said lever being arranged to actuate said dial indicator, the other arm of said lever being arranged in the path of movement of one of said stop surfaces, a rotatable cam to rock said platen, said cam being shaped to locate said platen in one of a plurality of positions, and a manually operable lever to actuate said cam.
